[57] CLAIM

The ornamental design for an air cylinder, as shown and described.

DESCRIPTION

FIG. 1 is a front elevational view of an air cylinder showing my new design;

FIG. 2 is a rear elevational view;

FIG. 3 is a right side elevational view;

FIG. 4 is a left side elevational view;

FIG. 5 is a right, front and top perspective view;

FIG. 6 is a right side elevational view of an air cylinder showing a second embodiment of my new design, the only difference from the embodiment shown in FIGS. 1 through 5 being the variation in length;

FIG. 7 is a right side elevational view of an air cylinder showing a third embodiment of my new design, the only difference from the embodiment shown in FIGS. 1 through 5 being the variation in length;

FIG. 8 is a top plan view of FIG. 1;

FIG. 9 is a bottom plan view of FIG. 1;

FIG. 10 is a cross sectional view taken along lines 10—10 of FIG. 3; and,

FIG. 11 is a cross sectional view taken along lines 11—11 of FIG. 1.

FIG. 1

FIG. 2

FIG. 3

FIG. 4

FIG. 5

FIG. 6

FIG. 7

FIG. 8

FIG. 9

FIG. 10

FIG. 11
